UNITED STATES PATENT OFFICE.

FRANK TODD, OF MINNEAPOLIS, MINNESOTA.

RADIATOR FOR GAS ENGINES.

1,413,302.

Specification of Letters Patent. Patented Apr. 18, 1922.

Application filed February 13, 1919. Serial No. 276,844.

To all whom it may concern:

Be it known that I, FRANK TODD, a citizen of the United States, resident of Minneapolis, county of Hennepin, State of Minnesota, 5 have invented certain new and useful Improvements in Radiators for Gas Engines, of which the following is a specification.

The object of my invention is to provide a radiator of such construction that any section 10 or any individual pipe therein will be easily accessible for substitution or repairs, special provision being made for closing the joints between the adjacent pipes to eliminate as far as possible danger of leakage.

15 A further object is to provide a radiator of simple construction, composed of comparatively few parts and hence inexpensive to manufacture and maintain.

20 A further object is to provide a radiator in which the use of gaskets in the joints and bolts passing through the water channels are eliminated.

25 A further object is to provide a radiator in which the tubes can be arranged vertically or horizontally, as desired, and any unit or section can be removed without taking the radiator off the car.

The invention consists generally in various constructions and combinations, all as 30 hereinafter described and particularly pointed out in the claims.

In the accompanying drawings forming part of this specification,

35 Figure 1 is a front view of a portion of a radiator embodying my invention,

Figure 2 is a vertical sectional view through the radiator, showing the manner of mounting the pipes therein,

40 Figure 3 is a detail sectional view, showing the preferred form of ground joint between the pipes,

Figures 4 and 5 are detail views of the clamp by means of which the pipes are held in assembled relation in the radiator.

45 In the drawing, 2 represents the head or top of the radiator, having a water chamber 3 therein and 4 the foot or base having a corresponding water chamber 3'. These parts 2 and 4 are preferably of casting and 50 extend from side to side of the radiator and are held in parallel relation by suitable bracing means, such as bars 5. The opposite walls of these chambers 3 and 3' are preferably recessed, as shown in Figure 2, to 55 provide spaces 6 for the insertion of the circulating tubes between the chambers, and

vertical extensions 7 are provided at the rear of the chambers for communication of the circulating tubes therewith. There may be any suitable number of the circulating 60 tubes in each group and as many groups arranged side by side as the length of the radiator demands. In the drawing I have shown each group composed of four tubes, but this number may, of course, be increased 65 or decreased, as desired.

8 represents the circulating tubes, the inner ones having nipples 9 formed on the ends thereof, each nipple having a flaring seat 10 at one end and a tapered section 11 at 70 the other end terminating in a straight portion 12 between which and said tapered portion an obtuse angle is formed. The tapered end of the nipple fits into the flaring seat of the adjacent nipple, which is provided with 75 a shoulder 13 to fit the angle between the straight and tapered portions 12 and 11, so that when the tubes are assembled, the joints between the nipples will be broken and any sediment entering the joint will lodge in the 80 angle and aid in preventing leakage between the tubes.

The wall section 14 of each of the chambers 3 and 3' has an opening 15 therein to receive the tapered ends of the inner nipples, 85 said opening fashioned to fit the tapered and straight portions of the nipple and form a close joint therewith. The next tube will have its nipple seated in the flaring end of the nipple of the first tube and so on to the 90 outer end of the group, where the tube is provided with a nipple 16 having a closed concave end wall 17 against which one arm 18 of a spider 19 is seated. A bolt 20 is tapped into the front wall of the water 95 chamber and passes through the spider 19 and an arm 21 is provided on said spider for bearing on said wall within a socket 21 therein. This manner of mounting the spider on the wall of the water chamber 100 positively holds it in position thereon.

Two of the arms 18 are preferably provided to bear on the nipples of adjacent groups of tubes, as shown in Figure 1, and when the bolt 20 is tightened the spider will 105 be securely clamped on the wall of the chamber and the nipples will be pressed firmly together to close the joints between them and prevent leakage. Whenever desired, the nut on the bolt 20 may be loosened and thereupon 110 the tubes of two adjacent groups will be released from their pressure and may be sepa-

rated from one another to obtain access to the inner tubes or to the chambers with which they are connected.

I have shown the spiders adapted for 5 clamping two groups of tubes, but provision may be made for securing a greater number of them by providing additional arms on the spiders. The arrangement at the bottom of the radiator is substantially the same 10 as described with reference to the top and I will indicate the parts by the same reference numeral, with the addition of the exponent *a*. The circulating tubes are of ordinary construction and are provided with the 15 well-known radiating discs 22 secured at intervals thereon. I have only shown a portion of one end of the radiator; it being understood that the construction is the same from end to end and that as many groups 20 of tubes may be employed as are found necessary to obtain the desired radiating surface. The circulating tubes are interchangeable, being of similar construction, and as shown in Figure 3, instead of providing an 25 integral wall in the nipple of the outer tube, I may employ a removable cap 23, which is seated in the flaring end of the nipple and has the tapered and straight surfaces in angular relation to fit the correspondingly 30 shaped walls of the nipple. All these joints are suitably ground so that when the tubes are assembled in groups and locked together the radiator will be watertight.

In a radiator of this construction there 35 is some freedom of movement of the groups of tubes and of one tube upon another, so that the racking or twisting of the radiator when in use in a car will be compensated for and leakage will not be as likely to occur as 40 where the radiator is made in sections permanently secured together.

I have found that with a radiator made in this way damaged tubes can be easily and quickly replaced; the expense of manufacture is reduced, as each unit can be handled separately. I am also able to dispense with the work of skilled mechanics, as the parts can be readily assembled by the use of pliers or a wrench, no soldering being necessary. 45 By blocking off a damaged section the radiator can be used with one or more units cut off from the remaining units. The straight extensions on the tapered ends of the nipples provide a means for keeping the headers in 50 proper alignment and also aids in obtaining a more perfect joint between the tubes. With a radiator of this kind the radiating surface can be increased or decreased to 55 compensate for variations and weather conditions.

I claim as my invention:

1. A radiator for gas engines comprising a head having a water chamber therein, a base having a water chamber, circulating 60 tubes arranged in groups between said cham-

bers, said tubes having nipples formed on the ends thereof, one tube of each group having its nipples seated in openings in the walls of said water chambers and the remaining tubes of the group having their 70 nipples seated one within the other, said nipples having straight and flaring seat portions and means mounted in said head and base for clamping the nipples of the groups together. 75

2. A radiator for gas engines comprising a head having a water chamber therein, a base also having a water chamber, a series of water circulating tubes between said head and base, said tubes being arranged in 80 groups and having nipples at their ends fitting one within the other, and each nipple having a tapered end terminating in a straight portion at an angle to the tapered portion and the adjacent nipple having a flaring and a straight surface wherein said tapered and straight portions are seated. 85

3. A radiator for gas engines comprising a head having a water chamber therein, a base also having a water chamber, circulating 90 tubes arranged in groups between said chambers and communicating therewith, the tubes of said groups being arranged in parallel relation and having nipples at the ends thereof for interlocking one with the other to form a water-tight joint between the tubes, spiders having arms for bearing on the outer nipples of adjacent groups and on the walls of said chambers, and bolts passing through said spiders and tapped into said 100 walls for clamping the nipples of the groups of tubes together. 95

4. A radiator comprising a head having a water chamber, a base also having a water chamber, the opposite walls of said head and base having inwardly projecting portions at the rear thereof forming a recess between said portions and the front of said chamber, circulating tubes arranged in groups each tube of a group having a nipple at each end 105 thereof fitting the other nipples of the corresponding ends in said recesses, the nipples of the inner tubes being seated within openings in the projecting portions of said wall, and means mounted on said head and base 110 and engaging the nipples of the outer tubes of each group for pressing all the nipples of that group together, for the purpose specified. 115

5. A radiator comprising a head and a 120 base having water chambers therein, circulating tubes arranged in groups, the inner tube of each group having nipples communicating with the chambers of said head and base and the other tubes of each group having nipples communicating with one another and with said inner tubes respectively, spiders mounted on said head and base and having pairs of inwardly projecting arms seated in the nipples of the outer tubes of 125 130

adjoining groups for forcing the tubes of the same group together, and said spiders having also outwardly projecting arms seated in recesses in said head and base.

- 5 6. A radiator for gas engines comprising a head and base and side bars connecting the corresponding ends of said head and base for holding them in parallel relation, said head and base having inwardly projecting 10 rear portions, a series of circulating tubes interposed between said head and base and arranged in groups in front of projecting rear portions, the tubes of one group being in parallel relation with those of the adjacent groups and each group being removable from said head and base independently of the other groups, the inner tube of each group being seated in the inwardly projecting portions of said head and base for communication therethrough with said water chambers, and the remaining tubes of the same group being seated one upon the other to form a row extending to the front of the radiator, the outer tubes of the groups being 25 flush substantially with the forward walls

of the head and base and means mounted on said walls and bearing on the outer tubes of the groups for pressing them inwardly upon one another and upon their bearings in said projecting portions.

7. A radiator for gas engines comprising a head and a base having water chambers therein, circulating tubes arranged in groups between said chambers, each of said tubes having nipples formed on the ends thereof, 35 one end of each nipple being tapered and the other end having a seat to receive the tapered end of the adjacent nipple, the groups of tubes being arranged in rows with each tube of a group having its nipples 40 seated in the nipples of the preceding tube and means bearing on the tubes of each group for clamping all the nipples of that group together, release of the clamping means of a group of tubes allowing the removal of any tube of that group without disturbing the tubes of the other groups.

In witness whereof, I have hereunto set my hand this 31st day of January, 1919.

FRANK TODD.
